United States Patent Office

Des. 185,567
Patented June 23, 1959

185,567

CARVING KNIFE OR SIMILAR ARTICLE

Emil S. Polk, Scarsdale, N.Y.

Application December 29, 1958, Serial No. 53,959

Term of patent 14 years

(Cl. D22—3)

Fig. 1   Fig. 2   Fig. 3

Fig. 4

I claim:

The ornamental design for a carving knife or similar article, substantially as shown.
